ABSTRACT

The fluorescent lamp comprises a bulb and a layer consisting of a first fluorescent substance having the principal luminous spectrum in the visible ray region and a second fluorescent substance having the principal luminous spectrum in the Dorno ray range. The proportion of the first and second fluorescent substances is selected to radiate visible light fluxes and Dorno ray fluxes at a ratio substantially equal to that of the natural day light. The bulb has a thickness about 0.8mm and is composed of a soda-lime glass which does not transmit radiations of the wave length less than 295nm.

FLUORESCENT LAMP PROVIDING VISIBLE LIGHT AND DORNO RAYS

CROSS-REFERENCE TO RELATED APPLICATION

This application is the continuation-in-part of the application Ser. No. 34,848, filed May 5, 1970, and now abandoned.

BACKGROUND OF THE INVENTION

This invention relates to fluorescent lamps and more particularly to fluorescent lamps emanating Dorno rays.

Ultraviolet rays having a wave length ranging from 280 to 310nm are generally termed as health rays or Dorno rays. It is well known in the art that ultraviolet rays in this particular range of wave length manifest the erythema function, and act to convert ergosterol to vitamin D and to enhance renewal of mineral substances in the human body. The Dorno rays are contained in natural light in a small quantity (less than 1 percent of the total energy throughout the ranges of ultraviolet rays and visible rays) and are usually absorbed by the human body through exposed portions of the skin when a man takes a sun-bath or works in the outdoor, thus contributing to his health. When a man does not absorb the Dorno rays over an extended period of time favourable growth of the body is hindered. In addition unsatisfactory renewal of the mineral results in the rupture of the vital function thus decreasing resistance of the body against cold and disease. Accordingly for men who have little chance of enjoying a sun-bath owing to their indoor works it is necessary to give them the opportunity to absorb Dorno rays.

Compensation for adverse effects to vital body function may be accomplished by taking nutritive foods or medicines, but the efficiency of absorbing them is different from man to man and the absorption function is limited to particular organs. Further the effect of these nutritive foods or medicines is temporary.

It is therefore reasonable to irradiate the human body with a suitable quantity of Dorno rays under a prescribed program so as to utilize the vital reaction of the human body to realize overall continuous physiological effect.

Health fluorescent sun lamps have been developed to radiate Dorno rays at a high efficiency but such lamps radiate only bright line spectrum of mercury in the visible range. For example, with a 20-watt health ray fluorescent sun lamp, the luminous flux at a point one meter spaced apart from the lamp is only about 10 luxes so that it is impossible to use this lamp for general lighting use. Accordingly, where health ray irradiation is required in addition to the artificial illumination, for example in indoor, underground room, enclosed room, or the like, it is necessary to use ordinary fluorescent lamps together with such health ray fluorescent sun lamps in order to keep the health of men working under such an environment over a long time. This requires luminaires for both types of fluorescent lamps. In addition, conventional fluorescent sun lamps are expensive because they require glass tubes of a special composition which does not transmit light of the wave length of less than 280nm. Further, as health ray fluorescent sun lamps radiate a large quantity of Dorno rays their distribution is not uniform and results in excessive irradiation. These lamps require an accurate control of irradiation time. To prevent damage to the skin and to avoid

adverse effect on the physiological effect it is necessary to mount the health ray fluorescent sun lamps at high positions or to control the operation time thereof.

SUMMARY OF THE INVENTION

It is therefore an object of this invention to provide a new special fluorescent lamp capable of providing a suitable quantity of Dorno rays for men working in a space under artificial light over a long time thus improving their health.

Another object of this invention is to provide a novel fluorescent lamp which can emit from a single bulb both visible light rays and the Dorno rays at a ratio substantially equal to that of the natural day light.

According to this invention there is provided a fluorescent lamp comprising a bulb having a thickness of 0.7 to 0.9mm and made of soda-lime glass intercepting light of a wave length of less than 295nm, the soda-lime glass mainly consisting of SiO_2 , R_2O_3 and R'_2O bearing 58 - 72, 1 - 2 and 13 - 18 by parts by weight, a quantity of mercury sealed in the bulb, electrode means mounted in the bulb, and a fluorescent layer provided on the inner surface of the bulb, said layer consisting of a first fluorescent substance having the principal luminescent spectrum in the visible light region, and a second fluorescent substance having the principal luminescent spectrum in the Dorno ray region, the weight ratio of the first and second fluorescent substances ranging from 97:3 to 88:12. The first and second fluorescent substances may be applied as a mixture or as separate layers which are laminated or juxtaposed each other.

The reason why, according to this invention, the bulb should be formed of soda-lime glass with a thickness of 0.7 to 0.9mm is for the purpose of unfailingly intercepting the radiation of only light having a wave length of less than 295nm. If any of these requisite conditions is not satisfied, then there will not be obtained the above-mentioned effect. For instance, where the bulb has a thickness of less than 0.7mm, light having a wave length of less than 295nm will be emitted. Conversely where said thickness exceeds 0.9mm, the emission of even the Dorno rays will be obstructed.

Therefore, the bulb constructed as described above and the prescribed weight ratio of the first to the second fluorescent substance naturally have a close interrelationship. In other words, the material and wall thickness of the bulb and the ratio in which the first and second fluorescent substances are blended together constitute important parameters in order to ensure that only light having a wave length of less than 295nm has its passage intercepted whereas the Dorno rays are effectively radiated.

BRIEF EXPLANATION OF THE DRAWING

FIG. 1 shows a side elevation, partly broken away, of a fluorescent lamp embodying this invention; and

FIG. 2 is a plot illustrating luminous spectrum distribution of the lamp shown in FIG. 1.

DETAILED DESCRIPTION OF THE INVENTION

With reference to the accompanying drawing there is shown an embodiment of a low pressure mercury vapour discharge lamp constructed according to the teaching of this invention.

The lamp shown in FIG. 1 comprises an elongated cylindrical envelope or bulb 10, electrodes 11 mounted on the opposite ends of the bulb 10 and bases 12 seal-

ing the opposite openings of the bulb. The bulb 10 has a thickness of 0.7 to 0.9mm, and preferably of about 0.8mm, and is made of a soft glass or soda-lime glass having a composition shown in Table 1 below, which does not transmit lights of the wave length of less than 295nm.

TABLE 1

	Ex. 1	Ex. 2	Ex. 3
SiO ₂	72	58	69.9
R ₂ O ₃ (Al ₂ O ₃ + Fe ₂ O ₃)	2	1	1.98
CaO	6	0	0.4
MgO	3	0	3.5
R ₂ O(Na ₂ O + K ₂ O)	17	13	17.32
PbO	0	28	0
As ₂ O ₃	0	0	0.9
Sb ₂ O ₃	0	0	0.49

In the table, the composition is represented by parts by weight.

On the inner surface of the bulb 10 is applied a fluorescent layer 13 comprising a fluorescent substance having the principal luminous spectrum in the range of visible light and a fluorescent substance having the principal luminous spectrum in the region of the Dorno rays. The former fluorescent substance may be calcium halophosphate activated by antimony-manganese while the latter fluorescent substance may be zinc-calcium phosphate activated by thallium. The weight ratio of the former to the latter fluorescent substance is 96:4, preferably from 97:3 to 88:12. The layer 13 may be formed of a single layer comprising the mixture of said different fluorescent substances. Alternatively, the layer 13 may comprise two laminated layers or juxtaposed layers of different fluorescent substances. Small quantities of mercury and argon gas are sealed in bulb 10, the ratio of mercury to argon being equal to that of the conventional fluorescent lamps. Mercury may be sealed at a vapour pressure of 10^{-2} - 10^{-3} mm Hg, for example.

Usually, the quantity of irradiation (does) of Dorno rays is expressed in MPE units. A unit MPE represents the quantity of irradiation effective to provide minimum noticeable erythema which is produced on the skin several hours after irradiation of ultraviolet rays but disappears next day. While the unit MPE is different from one to another, on the average it amounts to about 0.7E-Viton-h/cm². It is known that it is required to irradiate Dorno rays of $\frac{1}{4}$ to $\frac{1}{10}$ MPE unit per day in order to maintain normal health condition. Irradiation of 2 MPE units results in considerable sun-burn while irradiation of excessive units of Dorno rays not only results in inflammation of the skin and eye but also causes side effects such as tire, heart acceleration or the like.

The quantity of Dorno rays emanated from the fluorescent lamp of this invention amounts to about 1.4×10^3 E-Viton in a 40-watt health ray fluorescent lamp containing 6 percent by weight of the fluorescent substance and operating in the Dorno ray region. When this lamp is operated with an illuminating fixture with a white reflecting surface and utilized for conventional lamps the intensity of irradiated Dorno rays is 0.01 E-Viton-h/cm² at a point where the intensity of the visible light emanated from the novel lamp is 500 luxes, which is a standard value preferred for ordinary operations. At this point the workman will receive a total of 0.08 E-Viton-h/cm² during his working time of 8 hours, for example, thus receiving a suitable quantity of Dorno rays (about 1/9 MPE) required for maintaining

his health. Where intensity of the visible light is increased to 2,000 luxes as preferred by the illumination standard, the quantity of Dorno rays irradiated during the working time of 8 hours, for example, will be about $\frac{1}{2}$ MPE. Such a quantity of irradiation of the Dorno rays does not cause sun-burn of human skin even taking into consideration the personal difference in the sensitivity of the human body to ultraviolet rays.

Above described embodiment of this invention radiates a total light flux of 2500 lumens thus providing sufficient illumination for various operations.

Describing in more detail, the horizontal light intensity of the natural light (sun light plus heaven light) at noon in a fine day in midsummer is typically above 92,000 luxes while the Dorno rays amount to about 2 E-Viton/cm² (from Luckiesh data, in U.S.A.). According to the measurement in the city of Kawasaki, Japan, at 1 P.M. on a fine day in May, the intensity of the Dorno rays which was determined from the measured values of the spectrum distribution of the natural light multiplied by the rate of erythema was about 0.5 E-Viton/cm². The intensity of the horizontal illumination at that time was about 50,000 luxes.

The intensity of the Dorno rays in the same ratio as the natural light was determined to be about 0.022 E-Viton/cm² from the former and to be about 0.01 E-Viton/cm² from the latter respectively, where the intensity of illumination was 1,000 luxes.

In contrast, with the above described embodiment of this invention, the intensity of the Dorno rays was about 0.02 E-Viton/cm² at portions of the intensity of illumination of about 1,000 luxes.

From this it will be clear that the lamp embodying this invention can provide the same ratio of visible light flux to Dorno ray flux as that of the outdoor natural light on fine days.

FIG. 2 shows a spectrum distribution of one embodiment of this invention, the ordinate representing the spectrum radiation intensity in $\mu\text{W}/\text{cm}^2$ of respective wave lengths at a distance of one meter while the abscissa the wave length in nm.

As can be clearly noted from FIG. 2, there is an appropriate and effective radiation output in the Dorno ray region and yet the lamp has a sufficiently large light output and a suitable spectrum distribution characteristic in the visible range.

As described above, the envelope of the lamp has a thickness of about 0.7 to 0.9mm and is made of soft glass or soda-lime glass which does not transmit ultraviolet rays of the wave length of less than 295nm. Where a human body is exposed over a long time to radiations of high luminous intensity emanated from the lamp of this invention, no physiological trouble is caused by the irradiation of ultraviolet rays of short wave length.

As described above, it is advantageous to select the proportion of incorporation of the fluorescent substance having the principal luminous spectrum in the Dorno ray region to be from 3 to 12 percent, by weight, based on the total quantity of the fluorescent substances. With a quantity less than 3 percent, radiation of the Dorno rays becomes very small so that health ray radiations are very small. Whereas the quantity exceeds 12 percent, by weight, the quantity of health rays becomes excessive so that irradiation over a long period at a high luminous intensity is detrimental to health. Further, the visible output useful for illumination decreases. The effect of this invention is the maximum

when the quantity of the fluorescent substance emanating the principal luminous spectrum in the Dorno ray range amounts to 4 to 10 percent, by weight, based on the total quantity of fluorescent substances.

Thus, this invention provides a novel fluorescent lamp capable of providing sufficient and effective quantity of Dorno ray radiations contributing to the maintenance of the human health without the trouble of sun-burn at a place where the natural Dorno ray radiations from the sun is not available. Further, the novel lamp radiates the Dorno rays together with light rays suitable for illumination from a single fluorescent lamp. In addition, as the novel lamp does not radiate ultraviolet rays of short wave length no physiological trouble would result.

What is claimed is:

1. A fluorescent lamp for indoor use and emitting Dorno rays in approximately the same ratio to visible light as does the sun, comprising a bulb having a thickness of 0.7 to 0.9mm and made of soda-lime glass mainly consisting of SiO_2 , R_2O_3 and $\text{R}'_2\text{O}$ in the respective ratios of 58 to 72, 1 to 2 and 13 to 18, based on parts by weight, to intercept the radiation of light having a wave length of less than 295 nm through said bulb, wherein R is Al and Fe, and wherein R' is Na and K; a quantity of mercury sealed in said bulb; electrode means received in said bulb; and a fluorescent layer provided on the inner surface of said bulb, said fluores-

cent layer consisting substantially of a first fluorescent substance having a principal luminous spectrum in the visible light region, and a second fluorescent substance having a principal luminous spectrum in the Dorno ray region, and the weight ratio of the first to the second fluorescent substance ranging between 97:3 and 88:12.

2. The fluorescent lamp according to claim 1 wherein said layer consists of a mixture of said first and second fluorescent substances.

3. The fluorescent lamp according to claim 1 wherein said first fluorescent substance comprises calcium halophosphate activated by antimony-manganese and said second fluorescent substance comprises zinc-calcium phosphate activated by the thallium.

10 4. The fluorescent lamp according to claim 1 wherein the soda-lime glass comprises SiO_2 , R_2O_3 , CaO , MgO and $\text{R}'_2\text{O}$ bearing the ratio of 72:2:6:3:17 based on parts by weight.

15 5. The fluorescent lamp according to claim 1 wherein the soda-lime glass comprises SiO_2 , R_2O_3 , $\text{R}'_2\text{O}$ and PbO bearing the ratio of 58:1:13:28 based on parts by weight.

20 6. The fluorescent lamp according to claim 1 wherein the soda-lime glass comprises SiO_2 , R_2O_3 , CaO , MgO , $\text{R}'_2\text{O}$, As_2O_5 and Sb_2O_3 bearing the ratio of 69.9:1.98:0.4:3.5:17.32:0.9:0.49 based on parts by weight.
